BOTTLE

Dean H. Buchtel, Canton, Ohio, assignor to Robert C. Dye, Frank L. Buchtel, Harold H. Kehoe, and Edwin W. Oldham, fractional part interest to each

Filed Nov. 29, 1971, Ser. No. 203,127

Term of patent 14 years

Int. Cl. D9—01

U.S. Cl. D9—60

FIG. 4

FIG. 1

FIG. 2

FIG. 3

FIG. 5

FIG. 1 is a front elevational view of a bottle showing my new design;

FIG. 2 is a side elevational view;

FIG. 3 is a sectional view taken along the line 3—3 of FIG. 1;

FIG. 4 is a top plan view; and

FIG. 5 is a bottom plan view thereof.

The view of the rear of the bottle is exactly like FIG. 1 except it is flat without the recessed portion.

I claim:

The ornamental design for a bottle, substantially as shown and described.
